ELECTRIC SWITCH

John G. Jackson, Detroit, Mich., assignor to
 Square D Company, Detroit, Mich., a corpora-
 tion of Michigan

Application July 5, 1932, Serial No. 620,932

10 Claims. (Cl. 200—154)

This invention relates generally to electric switches and consists of certain novel features of construction, combinations and arrangements of parts that will be hereinafter more fully described and particularly pointed out in the appended claims.

One of the essential objects of the invention is to provide an electric switch having an improved quick make and break action.

10 Another object is to provide a switch wherein the quick make and break action is preferably accomplished by imparting an accelerated movement to the movable contact carrying member.

Another object is to provide a switch wherein 15 the movable contact carrying member is mounted for limited rotary movement in opposite directions between a pair of opposed arc suppressor plates.

Another object is to provide a switch wherein 20 the movable contact carrying member has means cooperating with the opposed plates to control the effect of the arc created upon disengagement of the movable contact means for the stationary contact means.

25 Another object is to provide a switch wherein the arc suppressor plates are preferably formed of fiber.

Another object is to provide a switch wherein 30 the stationary contact means is free with respect to but serves to limit movement of the arc suppressor plates laterally from the movable contact carrying member.

Another object is to provide a switch wherein 35 means independent of the mounting means for the arc suppressor plates is utilized for spacing said plates the proper distance apart.

Another object is to provide a switch wherein means is provided on the base for holding the fiber arc suppressor plates against turning and 40 for limiting turning or rotary movement of the movable contact carrying member in opposite directions.

Another object is to provide a switch wherein 45 the means for turning or rotating the movable contact carrying member is preferably in the form of a tongue-like projection at the forward edge of the movable contact carrying member.

Another object is to provide a switch wherein 50 means is provided for effecting a pressure between the movable and stationary contacts when the movable contact carrying member is in the "on" position and for holding the said member against movement in the "off" position.

Another object is to provide a switch wherein 55 the movable contact carrying member and oper-

ating handle are so constructed and arranged that the handle is always accessible at the front of the switch.

Another object is to provide a switch wherein 5 the parts are adapted for use in a cabinet or other suitable enclosure and may be operated from the exterior of such enclosure.

Another object is to provide an improved switch 10 which is simpler and cheaper in construction and is easier to operate than the more complex quick make and break devices on the market.

In the accompanying drawings:

Figure 1 is a perspective view of the switch and showing parts broken away and in section;

Figure 2 is a sectional view taken on the line 15 2—2 of Figure 3 and showing by full lines the "On" position of the disc and by dotted lines the "Off" position thereof;

Figure 3 is a sectional view taken on the line 20 3—3 of Figure 2;

Figure 4 is a detail view of the rotary disc;

Figure 5 is a vertical transverse sectional view 25 through the switch;

Figure 6 is a detail view of one of the insulating plates;

Figure 7 is a perspective view of a slightly modified form of construction.

Referring now to the drawings, E is a switch embodying my invention. As shown, the switch 30 E is the disc type and preferably includes a base 5 of insulating material, a shaft 6 journaled in upright portions or posts 7 and 8 respectively

of the base, a pair of thin and somewhat flexible plates 9 and 10 respectively of insulating material such as fiber on the shaft 6 between the 35 posts 7 and 8, a rotary disc 11 of insulating material on the shaft 6 between the plates 9 and 10, electric contacts 12 and 13 respectively embedded in the disc 11 in stepped relation to the shaft 6, and electric contacts 14 and 15 respectively of substantially L configuration on the base 5 and engageable with the contacts 12 and 13 in the disc. As shown, the posts 7 and 8 are spaced apart transversely of the base 5 and are provided in their upper ends with aligned grooves 40 16 and 17 that receive the shaft 6. A single plate 18 secured by a screw 19 to the post 8 over the groove 17 serves to hold the shaft 6 in the grooves 16 and 17. The plates 9 and 10 have aligned peripheral recesses 20 and 21 respectively that receive a transversely extending rib 22 of the base 5. Consequently the plates are held against 45 turning movement on the shaft 6. These plates 9 and 10 also have aligned substantially square shaped openings or windows 23 and 24 respec-

tively therein at substantially diametrically opposite points of the shaft 6 and have straight edges 25 and 26 respectively, substantially parallel to the partition member 3. The disc 11 is provided at substantially diametrically opposite points thereof with a longitudinally curved tongue-like radial extension 27 and a circumferentially extending recess 28. Preferably the extension 27 serves as an operating handle, while the recess 28 receives the rib 22 of the base 5 whereby the turning movements of the disc 11 on the shaft 6 are limited. Opposite sides of the disc have recesses 29 and 30 respectively separated by radially extending ridges 31 and 32 respectively and normally closed by the plates 9 and 10. Opposite sides of the contact 12 are within the recesses 29 adjacent and at substantially acute angles to the ribs 32 and are substantially in line with opposite sides of the disc, while opposite sides of the contact 13 are in the recesses 30 adjacent and at substantially acute angles to the ribs 31 and are substantially in line with opposite sides of the disc. The sides 33 and 33' of the ribs are quite abrupt, in fact, almost at right angles to the bases of the recesses 29 and 30, while the sides 34 and 34' of the ribs are inclined from their outer edges to the bases of said recesses. The bases 35 and 36 respectively of the L contacts 14 and 15 are fastened by bolts 37 and 38 to suitable electric connectors 39 and 40 respectively in the base 5, while the upright arm portions 41 and 42 respectively of said contacts have opposed inwardly offset coacting portions 43 and 44 respectively disposed in the openings 23 and 24 in the plates 9 and 10 and engageable with the contacts 12 and 13 in the disc 11 when the latter is in "On" position. Preferably these offset portions 43 and 44 of the contacts 14 and 15 are urged constantly toward each other by the inwardly offset end portions 48 and 49 respectively of substantially L-shaped spring backers 50 and 51 fastened by the bolts 37 and 38 respectively upon the bases 35 and 36 respectively of the contacts 14 and 15.

In use when the disc 11 is in "Off" position the offset portions 43 and 44 of the contacts 14 and 15 engage the bases of the recesses 29 and 30 adjacent the inclined sides 34 and 34' of the ribs. As the disc 11 is turned by the handle 27 from "Off" to "On" position the offset portions 43 and 44 of the contacts 14 and 15 travel up the inclined sides 34 and 34' of the ribs so as to be spread apart and upon passing over the edges of said ribs snap into engagement with the contacts 12 and 13. As the disc 11 is turned from "On" to "Off" position the offset portions 43 and 44 of the contacts 14 and 15 move from the contacts 12 and 13 over the edges of the ribs 31 and 32 and thence down the inclined sides 34 and 35 to the bases of the recesses 29 and 30. Thus a snap action is obtained from "Off" to "On" or from "On" to "Off" positions. As a result the contacts aforesaid are not apt to be burnt when the current is ruptured. The construction and arrangement of the disc recesses and plates 9 and 10 are such that restricted arcing chambers are provided between the disc 11 and plates 9 and 10. In this connection it will be noted that the ribs 31 and 32 form certain sides of the recesses 29 and 30, consequently said ribs not only serve as obstacles to cause the offset portions 43 and 44 of the contacts 14 and 15 to spread apart whereby they may snap from "Off" to "On" position or from "On" to "Off" position but also cooperate with the plates 9 and 10 to confine the arcs dur-

ing movement of the disc 11 with the contacts 12 and 13 relative to the contacts 14 and 15. As a result the extent of such arcs on the rupturing of the current is greatly reduced.

The spring backers 50 and 51 serve the double purpose of causing a quick make and break snap action of the contacts 14 and 15, and also while the switch is at rest in the "On" position contribute pressure to the contacts 14 and 15, thereby greatly reducing the energy loss in such contacts. Moreover, such backers also provide the contact pressure necessary to effect low contact resistance. It should also be noted that the insulating plates 9 and 10 above referred to may be employed to assist in closing or sealing the opening 64 in the partition member 3 and/or the opening 70 in the cover 2 receiving the handle 27 of the disc.

In Figure 7 I have illustrated a slight modification in which the plates 80 and 81 respectively have straight substantially parallel side edges 82 and 83 respectively and have straight substantially parallel outer edges 84 and 85 respectively. Spacer blocks 86 are located between and secured to said plates at the corners 87 and 88 thereof and have curved inner edge portions 89 conforming in shape to the periphery of the intermediate rotary disc 11. Thus such spacers 86 and their fastening members 86' not only serve to close the end portions of the slots 64 and 70 but also serve to maintain the plates 80 and 81 in proper close relation to the disc 11.

As shown, the base 5 constitutes a rear support for the switch structure, however, it is apparent that the rear support may be something other than such base and constructed and arranged to perform the functions thereof.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim as my invention is:

1. In an electric switch, a rotary plate-like member, contact means carried by the plate-like member, insulating plates engaging opposite faces of the plate-like member, fixed contacts engageable with the contact means carried by the plate-like member in the "On" position of the switch, and a single means cooperating with the insulating plates aforesaid to seal off the contact means and cooperating with the fixed contacts to impart a snap movement to the plate-like member.

2. In an electric switch, a rear support, a shaft substantially parallel with the front face of said support, spaced arc suppressor plates receiving said shaft and held against movement about said shaft by a part on the rear support, said plates having windows therein, a rotary plate-like member of insulating material on the shaft between said plates, electric contact means carried by the plate-like member and having contact faces at opposite sides thereof constantly between said plates but adapted when the plate-like member is rotated to register with the windows in said plates, and electric contact means carried by the support and extending freely through said windows for engagement with the contact means aforesaid when in registration with said windows.

3. In an electric switch, a rear support, a forward support in front of said rear support, a

- pair of opposed arc suppressor plates mounted on said forward support and held against turning movement by a part on the rear support, said plates having windows therein, a plate-like member of insulating material carried by said forward support between said plates for limited rotary movement in opposite directions, electric contact means carried by the plate-like member, registrable with said windows, and electric contacts projecting forwardly from the rear support upon the outer sides of said plates and having portions extending freely through said windows and engageable with the contact means carried by the plate-like member to establish a circuit through the switch.
4. In an electric switch, a rear support, a forward support in front of said rear support, a pair of opposed arc suppressor plates mounted on said forward support in front of said rear support, said plates being interlocked with the rear support and having windows therein, a plate-like member of insulating material mounted on said forward support between said plates for rotary movement in opposite directions in front of said rear support, said plate-like member being limited in both directions by a part on said rear support, electric contact means carried by the plate-like member and registrable with said windows, and electric contacts projecting forwardly from the rear support upon the outer sides of said plates and having portions extending freely through said windows and engageable with the contact means carried by the plate-like member to establish a circuit through the switch.
5. In an electric switch, a rear support, a shaft-like member supported in front of said support, a pair of opposed stationary arc suppressor plates receiving said shaft-like member, said plates having windows therein, a plate-like member of insulating material carried by said shaft-like member between said plates for limited rotary movement in opposite directions, electric contact means carried by the plate-like member, and registrable with said windows, electric contacts carried by the rear support and disposed upon the outer sides of said arc suppressor plates, said electric contacts being free with respect to said plates and having portions extending freely through said windows for engagement with the contact means carried by the plate-like member to establish an electric circuit through the switch, and means for turning the plate-like member in opposite directions to make and break the electric circuit including a handle element projecting substantially radially from an edge of said plate-like member.
6. In an electric switch, a pair of opposed stationary electric contacts, a plate-like member of insulating material mounted for limited rotary movement in opposite directions between said contacts from an "off" position to an "on" position and vice versa, electric contact means carried by said member engageable with the opposed contacts when the plate-like member is rotated to the "on" position to establish an electric circuit through the switch, and means for effecting a quick make and break action between the contact means and contacts including means operable when the plate-like member is in the "on" position to effect a pressure between the contact means and contacts and operable when the member is in the "off" position to hold the plate-like member against movement.
7. In an electric switch, a base, a plate-like member mounted for limited rotary movement in opposite directions on said base, plates of insulating material associated with said base and disposed on opposite sides of said rotary member in close proximity thereto, said plates having openings therein; electric contact means fixed to said base and having yieldable end portions extending through said openings, electric contact means carried by said rotary member and engageable with said yieldable end portions, and means on said rotary member cooperating with the yieldable end portions of the first mentioned contact means for imparting accelerated rotary movement to the plate-like member in either direction of rotation thereof.
8. In an electric switch, a base, a plate-like member mounted for limited rotary movement in opposite directions on said base, an arc-suppressor plate associated with said base and disposed in contiguous relation to a face of said plate-like member, said plate having an opening therein, an electric contact member fixed to said base and having a yieldable end portion extending through said opening, electric contact means carried by said plate-like member and engageable with said yieldable end portion, and means on said face cooperating with said yieldable end portion to effect snap acting engagement of the contacts and with said insulating plate to suppress arcing.
9. In an electric switch, a base, a plate-like member mounted for rotary movement on said base, plates of insulating material upon opposite sides of said plate-like member and having openings therein, electric contact means fixed to said base upon the outer sides of said plates and having yieldable end portions extending through said openings, electric contact means carried by said plate-like member and engageable with the end portions of the contact means aforesaid, spring means, and projections on said plate-like member, one of said projections extending from an edge of the plate-like member and forming an operating handle, and the other of said projections cooperating with the spring means to cause the engagement between the end portions of the first mentioned contact means and the last mentioned contact means to be snap like in action.
10. In an electric switch, a base having a pair of laterally spaced posts, a shaft carried by the posts, a pair of arc suppressor plates on the shaft between the posts having aligned openings and having aligned recesses therein, said plates being separate from the base, a rotary plate-like member of insulating material on the shaft between the suppressor plates and having a circumferentially extending recess in line with the aligned recesses in the plates, an electric contact element carried by said plate-like member, electric contacts fixed to the base and having yieldable portions extending through the openings in the plates for engagement with the contact element carried by the plate-like member, and means holding the plates against movement relative to the base and limiting movement of the plate-like member relative to said fixed contact elements including a stop on the base engaging the aligned recesses aforesaid.

JOHN G. JACKSON.
